UNITED STATES PATENT OFFICE.

EVERETT J. SAMPLES AND LOUIS C. McDONALD, OF KANSAS CITY, MISSOURI.

REFLECTOR.

Application filed June 21, 1922. Serial No. 569,950.

To all whom it may concern:

Be it known that we, EVERETT J. SAMPLES and Louis C. McDONALD, citizens of the United States, residing at Kansas City, in the county of Jackson and State of Missouri, have invented new and useful Improvements in Reflectors, of which the following is a specification.

One object of our said invention is the provision in a reflector of a shell adapted to be expeditiously and easily connected to and disconnected from a neck, this in order that the shell may be removed when dirty and replaced with a fresh shell, thereby obviating the danger of a workman cleaning the shell while it is in position for use.

Another object of the invention is the provision of peculiar and advantageous means for safely connecting the shell to the neck.

Another object is the provision of means for locking the lamp in the receptacle, and for guarding the said locking means when the shell is secured to the neck.

To the attainment of the foregoing, the invention consists in the improvement as hereinafter described and definitely claimed.

In the accompanying drawings, forming part of this specification:—

Figure 1 is a side elevation showing our improvement complete as it appears when ready for use.

Figure 2 is a side elevation of the reflector shell per se.

Figure 3 is a longitudinal central section taken through the reflector complete.

Figure 4 is a transverse section taken through the neck and the securing means in the plane indicated by the line 4—4 of Figure 3.

Figure 5 is a detail view illustrative of the means for locking the lamp in the receptacle.

Figure 6 is a detail elevation of the key that we prefer to employ in connection with the said lock, the said key being designed to be carried by a party in charge of the reflector and the lamp therein.

Similar numerals of reference designate corresponding parts in all of the views of the drawings.

The reflector shell is designated by 1, and is provided with a tubular extension 2 extending from the reduced end of the shell and provided in its rear end with bayonet

slots 3 and near said end and between two of the slots 3 with an aperture 4.

The neck of the reflector is designated by 5 and is of general tubular form with a wire conduit 6 at its rear end. The said neck 5 is provided with spaced apertures 7 and is also provided with a comparatively large aperture 8, the apertures 7 being designed for the passage of screws 9, and the aperture 8 being adapted for the introduction of the key 10, Figure 6, the said key 10 comprising a handle 11 of dielectric material, and a metallic shank 12 socketed and secured in one end of said handle and projecting therefrom and having in its forward end a socket 13 of angular form in cross-section.

The screws 9 are headed and kerfed at their outer ends and are provided with smooth shank portions 14 and with reduced and threaded shank portions 15.

Within the neck 5 and opposite the apertures 7 and 8 is arranged a lamp receptacle 16 of dielectric material, and in the said receptacle 16 is a threaded metallic bushing 17 for the engagement of the threaded stem on an incandescent electric lamp; it being understood in this connection that the receptacle is equipped with the usual or any other appropriate terminals for cooperation with the filament terminals of the lamp referred to. The receptacle 16 is provided with apertures 18 for the reception of the portions 14 of the screws 9, and embedded and secured in the receptacle 16 are nuts 19 to receive the threaded portions 15 of the screws 9. Secured in the receptacle 16 is a threaded bushing 20 threaded through said bushing and provided with an inner pointed portion which extends through the bushing 17 so as to engage the stem of the lamp is a locking pin 21 the outer end of which is of angular form in cross-section for the engagement of the shank of the key 10 before referred to. Manifestly when the aperture 4 of the shell extension 2 is registered with the aperture 8 of the neck 5, the key 10 may be engaged with the locking pin 21 for the fastening or the unfastening of a lamp stem in the bushing 17. It will also be manifest that when the tubular extension 2 on the shell 1 is turned about its axis within the neck 5 in order to fasten the extension 2 in the neck, the aperture 4 will be carried out of coincidence with the aperture 8 so as to guard the pin 21 and prevent tampering.

therewith. It will also be appreciated in this connection that when the extension 2 is turned about its axis to engage the bayonet slots 3 with the screws 9, and the said 5 screws are turned inwardly and tightened, the tubular extension 2 will be strongly and safely secured in the neck 5 and in such manner that there is practically no liability of the shell being casually disconnected and 10 permitted to fall. When deemed expedient, however, in order to make assurance doubly sure a stay wire 22 may be interposed between and connected to the forward portion of the shell 1 and a portion of the building 15 equipped with my improvement.

In virtue of the capacity of the shell 1 of our novel reflector to be readily detached from the neck 5 it will be understood that when it is not feasible in the winter time to 20 wash the shell 1 while it is in position for use, the said shell may be expeditiously and easily replaced with a fresh and clean shell, the removal shell being cleaned in a shop and being used in lieu of the said fresh shell 25 after the latter has become dirty to such an extent as to materially diminish its reflecting capacity.

In addition to the function herein before ascribed to the screws, it will be noted that 30 the said screws serve to strongly hold the lamp receptacle in the neck.

It will also be appreciated that as a whole our improvement is simple, strong and inexpensive in construction, and is well adapted 35 to withstand exposure to the weather.

We have entered into a detailed description of the construction and relative arrangement of the parts embraced in the present and preferred embodiment of our invention 40 in order to impart a full, clear and exact understanding of the said embodiment. We do not desire, however, to be understood as confining ourselves to the said specific construction and relative arrangement of parts in 45asmuch as in the future practice of the invention various changes and modifications may be made such as fall within the scope of our invention as defined in our appended claims.

50 Having described our invention, what we claim and desire to secure by Letters-Patent, is:—

1. The combination of a reflector shell having a tubular extension and also having 55 bayonet slots in said tubular extension, a tubular neck having apertures, a lamp receptacle of dielectric material arranged in said neck, nuts secured in the said receptacle and screws extending through the apertures of 60 the neck and having smooth shank portions and also having reduced and threaded portions engaging the nuts in the lamp receptacle to retain the latter in position; the

said lamp receptacle being spaced from the wall of the neck, the tubular extension of the shell being interposed between the receptacle and the wall of the neck for turning of the shell to engage the bayonet slots with the smooth portions of the screw shanks, and the screws being adapted to be 70 tightened to secure the tubular extension of the shell between the neck wall and the periphery of the lamp receptacle.

2. The combination of a reflector shell having a tubular extension and also having bayonet slots in said tubular extension, a tubular neck having apertures, a lamp receptacle of dielectric material arranged in said neck, nuts secured in the said receptacle and screws extending through the apertures 80 of the neck and having smooth shank portions and also having reduced and threaded portions engaging the nuts in the lamp receptacle to retain the latter in position; the said lamp receptacle being spaced from the wall of the neck, the tubular extension of the shell being interposed between the receptacle and the wall of the neck for turning of the shell to engage the bayonet slots with the smooth portions of the screw shanks, the screws being adapted to be tightened to 90 secure the shell extension between the neck wall and the periphery of the receptacle, and the receptacle being equipped with a threaded bushing and a locking pin extending 95 through said bushing and arranged in its threaded bearing in the receptacle, and the tubular shell extension and the neck having apertures which are registered with each other and with the locking pin when the shell extension is unlocked from the neck. 100 and is guarded by an imperforated portion of the neck when the tubular extension of the shell is turned to lock it in the neck.

3. The combination of a reflector shell having a reduced tubular extension, a stationary neck to receive said extension; a lamp receptacle in the extension, and means detachably connecting the tubular extension in the neck and to the neck; the lamp receptacle being secured in the neck by the means through which the tubular extension is detachably connected to the neck, and the said lamp receptacle being provided with a threaded bushing and with a locking pin bearing in the receptacle and having a point penetrating said bushing, and the shell extension and the neck having apertures which are in registration when the shell is unlocked and are not in registration when the shell is locked, the neck aperture being coincident with the locking pin. 110 115 120

In testimony whereof we affix our signatures.

EVERETT J. SAMPLES.
LOUIS C. McDONALD.
